US0D1050425S

(12) **United States Design Patent** (10) **Patent No.:** **US D1,050,425 S**
(45) **Date of Patent:** **** Nov. 5, 2024**

(54) **CATHETER ANCHOR SYSTEM**

(71) Applicant: **TENSION SQUARE, LLC**, Port Charlotte, FL (US)

(72) Inventors: **Mychael Arnell Overstreet**, Port Charlotte, FL (US); **Sonya Yvonne Overstreet**, Harker Heights, TX (US)

(73) Assignee: **TENSION SQUARE, LLC**, Port Charlotte, FL (US)

(**) Term: **15 Years**

(21) Appl. No.: **29/833,649**

(22) Filed: **Apr. 6, 2022**

(51) LOC (14) Cl. **24-02**

(52) U.S. Cl.

USPC **D24/128**

(58) **Field of Classification Search**

USPC D24/127-129; D11/200-212, 222;

D8/382-383, 394, 330-331, 339

CPC A61M 25/02; A61F 5/08; A61F 13/0216;

A61F 13/00063

(57) **CLAIM**

The ornamental design for catheter anchor system as shown and described.

DESCRIPTION

FIG. 1 is a top perspective view of a catheter anchor system in accordance with the new design in a closed position;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a top perspective view of FIG. 1 in an open position.

The broken lines in the drawings illustrate portions of the catheter anchor system and form no part of the claimed design.

1 Claim, 7 Drawing Sheets
